29/571,996.*Primary Examiner* — W. A. Teddy Falloway*(74) Attorney, Agent, or Firm* — Scully, Scott, Murphy &
Presser, P.C.(57) **CLAIM**

The ornamental design for a carrier, as shown and described.

DESCRIPTION

FIG. 1 is a perspective view of the carrier showing our new
and ornamental design;

FIG. 2 is a top view thereof;

FIG. 3 is a side view thereof; and,

FIG. 4 is a front view thereof.

The side view depicted in FIG. 3 is a mirror image of the
opposite side view, which is not depicted herein. The front
view depicted in FIG. 4 is a mirror image of the back view,
which is not depicted herein. The broken lines are included
for the purpose of illustrating portions of the carrier that
form no part of the claimed design.**1 Claim, 4 Drawing Sheets**(56)
